UNITED STATES PATENT OFFICE.

PHILLIP T. HUCKABAY, OF GREENVILLE, GEORGIA.

WELL-BUCKET.

1,111,584.

Specification of Letters Patent.

Patented Sept. 22, 1914.

Application filed February 14, 1913. Serial No. 748,483.

To all whom it may concern:

Be it known that I, PHILLIP T. HUCKABAY, a citizen of the United States, residing at Greenville, in the county of Meriwether 5 and State of Georgia, have invented certain new and useful Improvements in Well-Buckets; and I do hereby declare the following to be a full, clear, and exact description of the invention, such as will enable others 10 skilled in the art to which it appertains to make and use the same.

This invention relates to well buckets and is designed to construct a bail for use in connection with wells which will insure the 15 positive filling of the bucket to the brim. Heretofore in the construction of well buckets the bail has been pivotally connected thereto, adjacent to the top of said bucket in such a manner that said bucket after the 20 same has been partially filled will float upon the top of the water, thus necessitating the vertical reciprocation of the rope or chain in order to fill the bucket. This reciprocation makes the well muddy and constantly keeps 25 it in this state. By the provision of the present invention the bucket positively fills without the necessity of sticks or other similar means which have been used heretofore to retain the bails of well buckets rigidly.

30 With the above and other objects in view, this invention consists in the construction, combination and arrangement of parts, all as hereinafter more particularly described, claimed and illustrated in the accompanying 35 drawings, wherein: the figure illustrates in perspective a well bucket constructed in accordance and provided with the bail forming the subject matter of the present invention.

In carrying out the present invention a 40 well bucket of any suitable shape, size, etc., is utilized and is provided at its upper terminal, adjacent to the brim, with a curved bail which is rigidly secured to the walls of said bucket and completely surrounds the bucket with respect to its longitudinal dimensions, the terminals of said bail being diametrically disposed for the purpose of retaining the equilibrium of the bucket when the same is removed from the well.

45 Referring more particularly to the draw-

ings, 10 indicates a well bucket of any suitable construction, preferably bilged, as illustrated. A plurality of metal hoops 11 encircle and form a rigid structure therewith.

A U-shaped bail 12 of material of tubular 55 form having its arms 13 flat, is secured to said bucket through the medium of the said arms. These arms in the illustration extend throughout the entire height of the receptacle and are riveted through the bucket to 60 the hoops 11, thereby not only securing the bail to the bucket, but likewise rigidly securing the hoops thereto. One of the arms 13 is bent under the bottom of the bucket and has its terminal 14 bent upwardly and 65 riveted to the lower terminal of the opposite arm 13. When so desired the arms 13 may terminate at the second hoop 11 from the brim of the bucket 10, eliminating the structure adjacent to the bottom of said bucket. 70 Either of the structures may be used without departing materially from the spirit of the invention.

It has been found by actual experience that the pivotally connected bails do not permit buckets to be entirely filled without primarily reciprocating the rope or support in such a manner as to stir the water and fill the bucket. In order to overcome this feature it has been customary to interpose sticks between the vertex of the bail and the bottom of the bucket in order to retain the bail rigidly, thereby permitting the bucket to immediately fill. The present invention eliminates these sticks and causes the weight 80 of the bail to rest entirely upon the brim of the bucket and not swing back and rest centrally against the sides thereof, as would be 85 the case if the said bail was pivotally connected to the said bucket.

Owing to the weight and the distance of the bail from the top of the bucket, when the bucket is let down into a well and strikes the water the bail 12 has a tendency to carry the upper edge of the bucket down into the water to assist in filling the same, and when the well rope is drawn upward the bucket is not liable to be swung upon its bail to spill the water, thus insuring a bucket full at each 90 operation of the well rope.

Having thus fully described my invention, what I claim as new, and desire to secure by U. S. Letters Patent, is:—

5 A well bucket having metal hoops encircling the same, and a combined bail and side supporting element comprising a metal tube flattened for a portion of its length and secured at the opposite sides of the bucket to said hoops and said bail being tubular and
10 extended at some distance from the upper

edge of the bucket to serve as an overweight to insure the tilting of the bucket in the well to fill the same.

In testimony whereof I affix my signature in presence of two witnesses.

PHILLIP T. HUCKABAY.
